(57) **CLAIM**

The ornamental design for a triangular bed for animals, as shown and described.

DESCRIPTION

FIG. 1 is a front perspective view of a triangular bed for animals, showing my new design;

FIG. 2 is a front plan view thereof;

FIG. 3 is a rear plan view thereof;

FIG. 4 is a right side plan view thereof;

FIG. 5 is a left side plan view thereof;

FIG. 6 is a top plan view thereof; and,

FIG. 7 is a bottom plan view thereof.

In the drawings, the broken lines depict portions of the triangular bed for animals that form no part of the claimed design.

1 Claim, 7 Drawing Sheets
